UNITED STATES PATENT OFFICE.

RAGNAI O. W. LUNDIN, OF NORTH ATTLEBORO, MASSACHUSETTS, ASSIGNOR TO BARBER ELECTRIC MANUFACTURING COMPANY, OF NORTH ATTLEBORO, MASSACHUSETTS, A CORPORATION OF MASSACHUSETTS.

ELECTRIC SWITCH.

1,370,138.

Specification of Letters Patent. Patented Mar. 1, 1921.

Application filed April 17, 1919. Serial No. 290,677.

To all whom it may concern:

Be it known that I, RAGNAI O. W. LUNDIN, a citizen of the United States, and resident of North Attleboro, in the county of Bristol and State of Massachusetts, have invented certain new and useful Improvements in Electric Switches, of which the following is a specification.

The present invention relates to switches of a type generally used for household service and in which the switch elements, circuit terminals and fuses are inclosed within a covered box-like casing. The switch is operated by means of an external handle and provision is made to prevent improper operation of said handle to throw the switch into the "on" position, when the lid, covering the switch box, is opened to obtain access to the switch and fuses.

10 The present invention may generally be described and compared to show similarity to known types of switches in that the present construction includes a covered box member, containing the electric circuit terminals, switch and fuses, and switch operating means arranged to coöperate with a lid covering the box, in a manner that before the lid can be opened, the switch will have to be operated to break the electric circuit, 15 and vice versa, before the switch can be operated to complete the circuit, the said lid must be moved into the closed position.

20 The object of the invention, among other things, is to produce a serviceable apparatus of a simple improved design, constructed with the minimum number of easily assembled parts, without lessening the efficiency of the apparatus.

25 An embodiment of the invention will be particularly described hereinafter with reference to the accompanying drawings wherein—

Figure 1 is a perspective view of a complete apparatus showing the switch operating handle in the "off" position;

Fig. 2 is a plan view showing the lid removed and a portion of the box broken away;

Fig. 3 is a fragmentary perspective view showing the lid, switch, and operating handle in the relative positions they are in when the switch is in the "off" position.

Fig. 4 is a detail view of a segmental plate movable with the switch handle and provid-

ing a bearing and locking means for the same and also a locking device for the lid.

Fig. 5 is a detail view of the switch operating handle showing the aforesaid segmental plate and said handle in various positions;

Fig. 6 is a detail view showing the reverse side of said segmental plate with a portion of a switch operating lever secured thereto, and

Fig. 7 illustrates a fragment of one side plate of the box having therein radius slots concentric with a central hole.

Referring now to said drawings, 1 designates the box-like casing constructed preferably of one piece of sheet metal and having the ends and corners thereof bent and secured together to form a rigid structure. A covering is provided for the box preferably in the form of hinged lid 2 having the raised portion 3 of polygonal or other suitable shape to provide clearance for the travel of the switch element contained within the box. For convenience in opening and closing the lid 2, knob 4 is provided and to permit locking of the lid in the closed position perforated ears 5 and 6 are formed respectively on said lid and at one end of the box for the reception of padlocks or other permanent locking means.

The knife blade switch 7, circuit terminals 8, fixed contacts 9', and fuse plugs 9, are mounted on the insulating base 10, and all of said parts are contained within the box 1. The switch is manually operated by means of the external handle 11, and the offset bar lever 12, which is united in coöperative relation with said handle 11. The free end of the lever 12 is loosely held within the hole 14 in insulated tie bar 13 between the switch blades 7 so as to permit development of a determined amount of lost motion whereby spring 14', between said tie bar 13 and lever 12, is extended and thereby put under tension when the handle 11 is manipulated to open the circuit and thus a quick break action of the switch can be obtained.

The handle 11, lever 12, and segmental locking plate 15, are united together by bolts 16 and move together as one unit on the central boss or bearing 17 of the plate 15, and which bearing 17 engages hole 18 in the side wall of the box 1. The bolts 16 travel in radius slots 19 arranged concentrically with

said hole 18 and through the medium of these slots, a wider bearing base is provided for the switch operating elements and furthermore, said slots limit the movement of the switch handle in both directions of rotation. In this connection, it may be noted, where it is not necessary to permanently lock the switch handle, the slotted offset ear 20 of the handle and engaging slotted abutment plate 21, secured to the box, may be dispensed with.

The segmental plate 15 is provided with a pair of holes 22, which register with holes in the base 23 of the handle 11 through which latter holes the bolts 16 pass, and by these means the handle is secured in coöperative relation to the plate 15. The flattened end 24, of the lever 12, is secured to the plate 15 by means of the bolts 16 and these bolts, thus besides providing an extended bearing and stops for the handle and other switch operating elements, also serve to unite said elements.

A flange 25 is formed at one end of the segmental plate 15 and this flange with the sunken portion 26 of the plate 15 forms a housing for a pivoted latch member 27. One end of this latch member is held by spring 28 in contact with the underside of the flange 25, and when in this position, any movement of the switch handle, in a clockwise direction, is prevented by engagement of the free extremity of the latch 27, with a stop pin 29, projecting inwardly from the side plate of the box 1. The engagement of the latch 27 and the pin 29 will take place so long as the lid 2 of the box is open, and consequently the switch cannot then be moved in a clockwise direction to close the electric circuit.

The turned over edge 30 of the lid 2 carries an inwardly projecting trip pin 31 which will register with and enter the open slot 32 formed in the edge of the side plate of the box, when the lid is closed. The pin 31 will then also enter slot 32 in flange 25 and depress the latch 27 into the position shown by broken lines in Fig. 5, and in this position of the latch, the latch will be released from engagement with the pin 29 and then the switch handle and coöperating parts, may be moved into the position, also shown by broken lines in Fig. 5. In the latter position of the aforesaid parts the movable contacts 7 of the switch will be in contact with the fixed contacts 9 and the electric circuit is then closed.

It will be understood the switch handle 11 can be operated at any time to break the electric circuit, but when the switch and coöperating parts are in the position to close the circuit, the lid 2 cannot be opened because the pin 31, carried by the lid 2, lies under the flange 25, and until the segmental plate 15 is moved in an anti-clockwise direc-

tion, to such an extent that the switch is thrown to break the circuit and the slot 32 again registers with the pin 31, the lid cannot be opened.

The impossibility of opening the switch box when the circuit is closed and of closing the circuit carelessly when the box is open, eliminates danger to inexperienced persons, who may for example have occasion to replace a blown out fuse.

75

Possible variations may be made from the precise embodiment of the invention herein shown and described without departing from the spirit of the invention as defined in the appended claims and I therefore do not 80 wish to be limited to the precise details of the invention shown and described, but—

I claim—

1. In an electric switch of the class described having the switch element thereof 85 inclosed within a covered box and operable by external means, a locking member having a latch movably mounted thereon; said external means and locking member being united together so as to form one movable 90 unit; and a stationary stop on said box engaging said latch whereby operation of said movable unit is prevented.

2. In an electric switch of the class described having the switch element thereof 95 inclosed within a covered box and operable by external means, a locking member having a latch movably mounted thereon; said external means and locking member being united together so as to form one movable 100 unit; a stationary stop on said box engaging said latch whereby operation of said unit is prevented; a lid for said box; and a trip device on said lid engaging and releasing said latch in the closed position of said lid. 10

3. In an electric switch of the class described having the switch element thereof inclosed within a covered box and operable by external means, a locking member within 11 said box secured to said external means so as to form one movable unit; a latch device carried by said locking member; a fixed stop engaging said latch whereby operation of said unit is prevented; a lid for said box; a trip device on said lid engaging and releasing said latch in the closed position of said lid; and means on said locking member for engaging said trip device whereby said lid is locked in its closed position.

4. In an electric switch of the class described having the switch element thereof inclosed within a covered box and operable by external means; a locking member within said box united to said external means by securing devices so as to form one movable 12 unit; and a bearing for said unit permitting only a limited partial rotary movement of the said unit; said bearing comprising a central pivot and said securing devices which move about said pivot in a constrained path 13

defined by radius slots formed in one side of the box.

5. In an electric switch of the class described, a stationary base; a switch element mounted on said base; a lever for actuating said element; an operating handle; an intermediate member having a latch movably mounted thereon; means for uniting said lever, handle and intermediate member together so as to form thereof one movable unit; and a stationary stop engaging said latch to lock said movable unit in a determined position.

6. An electric switch comprising a switch element, an actuating lever for said element, an operating handle, an intermediate member, and means providing a common bearing and movement limiting stops for and serving to unite said lever, handle and intermediate member so that they will move as one unit.

7. An electric switch having a switch element; a box containing said element; a composite member for operating and controlling said switch element, said composite member comprising an actuating lever and a self-contained locking member located within said box and an operating handle located without said box, and means passing through radius slots in one side of said box for uniting the component parts of said composite member and limiting movement thereof.

8. An electric switch having a switch element, a box containing said element; a composite member for operating and controlling said switch element; said composite member comprising an actuating lever for said switch element, an operating handle and an intermediate locking member; the latter member and said actuating lever being located within said box and the said oper-

ating handle being located without the box; a central bearing for said composite member carried by said locking member and means uniting the component parts of the composite member and also providing an extended bearing for the latter member and limiting movement thereof through engaging slots in the side of the box arranged concentrically with said central bearing.

9. An electric switch having a switch element, a box containing said element; a lid for said box; a composite movable member for operating and controlling said switch element; said composite member comprising an actuating lever connected to said switch element, a locking plate or member and an external handle; a latch device carried by said locking member; a fixed stop on said box engaging said latch when said lid is open; and a trip device on said lid engaging and releasing said latch when said lid is in its closed position.

10. An electric switch having a switch element; a box containing said element; a lid for said box; an actuating lever for said switch element; an external handle for operating said lever; an intermediate member provided with a latch device; a stationary stop on said box engaging said latch device in the open position of said lid whereby said handle is locked against movement for closing the switch; a trip device on said lid engaging and releasing said latch in the closed position of said lid; and means on said intermediate member for engaging said stationary slot and locking said lid in a closed position when said switch element is in the position for closing an electric circuit.

Signed at North Attleboro in the county of Bristol and State of Massachusetts this 20th day of March A. D. 1919.

RAGNAR O. W. LUNDIN.
